UNITED STATES PATENT OFFICE.

PAUL T. CAMPBELL, OF BRIDGEPORT, CONNECTICUT.

SPARK-PLUG.

1,101,834.

Specification of Letters Patent. Patented June 30, 1914.

Application filed July 3, 1913. Serial No. 777,247.

To all whom it may concern:

Be it known that I, PAUL T. CAMPBELL, a citizen of the United States, residing in the city of Bridgeport, county of Fairfield, State of Connecticut, have invented certain new and useful Improvements in Spark-Plugs; and I do declare the following to be a full, clear, and exact description of the invention, such as will enable others skilled in the art to which it appertains to make and use the same.

This invention relates to certain new and useful improvements in spark plugs, and the object thereof is to provide a spark plug which has means incorporated therein for scouring the terminals of the electrodes to free same of oil, carbon, or other impurities.

Further the invention aims to provide means whereby the terminals may be adjusted relative to each other in order to bring same to sparking position.

In the drawings: Figure 1 is a vertical sectional view of the invention; Figs. 2 and 3 are fragmentary views similar to Fig. 1 but showing modified forms of my invention.

The invention consists primarily in the provision of a spark plug that has a hollow body or chamber closed at its lower or bottom end to provide a gas chamber that forms the lower part of the plug, and an elongated flared tubular portion which is connected to the central part of the chamber bottom and communicates with the interior of the chamber.

The body 1 of the spark plug has an opening 2 formed in its lower end, in which opening the base 3 of an elongated tubular part 4 is secured by cement or in any other suitable or approved manner. The bore 5 of the part 4 is conical in form and flares inwardly as depicted in Fig. 1 of the drawings. By providing a conical form of bore it provides a wedge-shaped wall, so to speak, that surrounds the terminal 6 so that during the working strokes of the piston, the charge in its movements past the terminal 6 will scour or clean the latter by being wedged thereagainst in an obvious manner. On the compression stroke, a part of the charge is forced into the plug body, through the smallest end of the bore 5 and due to the contracted nature of said smallest end, the charge will rush past the terminal with great force. The walls formed by the bore 5 are disposed in very close proximity to the terminal so as to insure intimate contact of

the charge with the terminal to enhance the scouring action, which latter is also augmented by the fact that the tubular parts are made long to thus assure intimate contact of the charge with the terminal throughout a greater portion of the length of the latter.

The tubular part 4 affords both the inlet and outlet for the plug interior or chamber, and the wall that the bore 5 provides forms the other terminal of the spark plug.

An additional advantage of the conical bore is, that, should the sparking distance between the terminals be too little, this may be remedied by shortening the terminal 6 so that its end may be higher up within the conical bore and therefore separated by a greater space from the wall of the latter, and this shortening of the terminal 6 may be effected in any suitable manner, either by making its normal length less or by adjusting the same by any ordinary means provided for the purpose of elevating or lowering the terminal.

I prefer to extend the tubular portion within the hollow chamber since a convenient receptacle is thereby formed at the bottom of such chamber for any liquefied gas, but I do not wish to be limited in this respect since such tubular portion may project downwardly from the bottom of such chamber, as shown in Fig. 3.

In Fig. 2 a modified form of the invention is shown in which the wall formed by the opening 2' in the plug bottom is threaded to receive the exteriorly threaded enlargement or boss 7 at the base of the tubular part, a lock nut 8 being engaged with the threads of the boss and with the outer face of the plug bottom.

In order to provide for the adjustability of the terminal 6 the latter is threaded throughout the greater portion of the length of its upper portion and engaged with a nut 9 which latter is stationary so that it will be readily understood that it is merely necessary to relax the lock nut 10 which engages the terminal at the top of the plug, and then turn the terminal either by means of a screw driver inserted within a slot 11 at the top of the terminal or in any other suitable manner.

From the above it will be apparent that the electrode terminals may be adjusted to increase or decrease the space between them, and that the wire 6 which forms one terminal is parallel with the axis of the bore 5.

the walls of which latter form the other terminal, and that said wire and axis extend in a direct line with the currents created by the compression and exhaust within the cylinders.

What is claimed is:

A spark plug having at its lower end a hollow gas chamber closed at the bottom the latter formed with an elongated tubular portion the bore of which is conical and flared upwardly and leads directly into said chamber and affords the sole inlet and outlet thereof, the inner wall of said bore forming one terminal of the plug, and an elongated bare wire extending through said hollow

chamber and terminating within said bore, and means for establishing the proper height of the end of said wire within said bore whereby the terminals may have proper spaced relation, said wire and the axis of said bore being substantially parallel with each other and extending in a direct line with the currents created by the compression and exhaust within the cylinders.

In testimony whereof I affix my signature in presence of two witnesses.

PAUL T. CAMPBELL.
